UNITED STATES PATENT OFFICE.

RAY H. MANSON, OF ELYRIA, OHIO, ASSIGNOR TO DEAN ELECTRIC COMPANY, OF ELYRIA, OHIO, A CORPORATION OF OHIO.

OPERATOR'S KEY.

No. 927,664.

Specification of Letters Patent. Patented July 13, 1909.

Application filed August 23, 1907. Serial No. 389,814.

To all whom it may concern:

Be it known that I, RAY H. MANSON, citizen of the United States, residing at Elyria, in the county of Lorain and State of Ohio, have invented a certain new and useful Improvement in Operators' Keys, of which the following is a full, clear, concise, and exact description, reference being had to the accompanying drawings, forming a part of this specification.

My invention relates to telephonic circuit changing apparatus, particularly to ringing and listening keys used in the cord circuit at the central exchange, the object of the invention being to eliminate some of the errors and operation difficulties caused by the defective operation of keys of this kind now in use.

Keys of this class usually comprise two sets of contact springs, one set controlling the connection of the operator's telephone set with the line, and the other controlling the connection of the ringing generator with the line, this latter set normally closing the cord circuit and when actuated disconnecting the answering part of the cord circuit and connecting the calling part thereof with the generator. A key lever is usually provided for controlling the operation of the spring sets, and a ball, roller or other parts, of insulating material, being usually carried by the key to engage the actuating springs of the spring sets. Means are also usually provided for locking the key lever in its actuated position after it has caused operation of the first set of springs to connect the operator's telephone set with the cord circuit, whereas the key lever will be held in its actuated position upon actuation of the ringing springs only so long as it is manually held there by the operator. The means for locking the key when moved to its listening-in position are usually spring means, and in most cases are the actuating springs themselves of the listening-in contact spring set, and when the key lever is released manually it is thrown back by spring power to and beyond its normal position. Also, in order that the key lever is held in its normal

position, it has been customary to balance the lever between the actuating springs of the listening-in and ringing sets, respectively. In these prior keys the ringing set, besides the actuating spring, has a normal contact spring and an alternate contact spring, the normal spring only being normally engaged by the actuating spring. In this arrangement, when the key lever is snapped back to normal from the listening-in position it is thrown against the actuating spring of the ringing set and causes disengagement of this actuating spring from the normal contact spring, which causes a disagreeable click to be heard in the calling subscriber's receiver. Where the cam lever is balanced between the actuating springs of the sets, the pressure of the ringing set actuating spring against the cam must be counteracted by the pressure of the listening-in actuating spring, and the ringing actuating spring is therefore restrained more or less from making contact with the inner or normal contact spring, and after a key is in service a short while the engagement between the inner and actuating springs is very likely to be broken. To overcome this it is customary to give the inside or normal spring a slight tension to cause it to follow the actuating spring a short distance, but this spring action soon wears out and the trouble referred to occurs.

To overcome all these difficulties is the main purpose of my invention, and I attain this by replacing the actuating springs by dummy springs in connection with the actuating or inner contact springs, the dummy springs being long to be engaged by the cam lever, and the inner contact springs may be made of the same length as the inner or alternate contact springs. These dummy springs are so adjusted that they must move a considerable distance before they will engage the contact spring to cause disconnection thereof from the normal contact spring and connection thereof with the alternate contact spring. Therefore, when the cam snaps back from the listening-in position there may be considerable overthrow thereof

and considerable movement of the dummy springs without in any way affecting the contact relations of the ringing set springs. The dummy springs can also be given any tension to assist in balancing the cam lever in its normal position without interfering with the ringing contact springs.

My invention will be better understood when described with reference to the accompanying drawing, in which—

Figure 1 is a side elevation view of a key incorporating my invention; Fig. 2 is a rear view thereof, parts being broken away to more clearly illustrate the arrangement; and Fig. 3 is a sectional view taken on line 3—3 of Fig. 2.

The key shown comprises the vertical supporting bar 1, and the top supporting bar 2 on which is mounted the escutcheon plate 3. In the opening 4 through the plates 2 and 3 extends the cam frame 5 of the key 6, this cam frame being pivoted at 7 in said opening in a well-known manner. At the lower end of the cam frame are pivoted the rollers 8, 8 and stop projections 9 and 10 on the cam frame engage against the top plate 2 to limit the rotation of the key. At the bottom of the supporting bar 1 are supported a plurality of vertical circuit-changing springs, a group being shown associated with each cam roller. Each group comprises an inner set of ringing circuit-controlling springs and an outer set of listening-in springs for controlling the operation of the operator's telephone set with the cord circuit. The inner set comprises the contact or actuating spring 11, the normal contact spring 12 and the alternate contact spring 13. Lying adjacent the contact spring 11 is a spring 14 which I call a dummy spring and which extends upwardly beyond the other springs into engagement with the corresponding cam roller. The contact spring 11 carries the contact point 15 for engaging with the contact point 16 on spring 13, and also carries a contact point 17 for engaging the contact point 18 extending from the normal contact spring 12. At the lower end all the springs are clamped together and secured to the supporting bar 1 by the screws 19, insulation strips 20 intervening to insulate the springs from each other and from the mounting bar, with the exception of the contact spring and the dummy spring, which lie directly in engagement with each other as shown. The dummy spring has the opening 21 through which projects the contact 18, this opening being sufficiently large to prevent contact of said point with the dummy spring. The contact springs 11 are given sufficient spring tension so that they will normally hold their contact points 17 in firm electrical engagement with the contacts 18, and springs 11 and 13 are normally disconnected. The length of each contact 18 is also such that

the spring 11 will normally be separated quite a distance from the dummy spring. When the cam lever is now rotated to carry the rollers against the dummy springs these springs will move through a considerable distance before engaging the contact springs 11 to disconnect these springs from the normal springs 12 and to connect them with the alternate springs 13, the exact purpose of which will appear later.

Each set of listening-in springs comprises a long actuating spring 22 having the outward end 23 engaged by the corresponding cam roller, while the contact spring 24 of the set is shorter, its contact point 25 being normally disengaged from the contact point 26 on the actuating spring. The lower ends of these springs are also held in place by the screws 19 and are separated by insulating strips 21', the sets of springs being separated by a main insulating block 27, as shown. The angle and position of the ends 23 is such that when the cam lever is rotated the cam rollers will engage the ends and the cam lever be held in its actuated position, and when the cam lever is given a slight touch toward its normal position it will jump or snap back to its normal position. The dummy springs 14 and the actuating springs 22 are given an inward spring tendency, so that they will engage the cam rollers to normally hold and balance the cam lever in a vertical position. This spring tendency can be given the dummy springs 14 without in any way affecting the ringing circuit springs. When the key lever is moved into locking engagement with the actuating springs 22 to connect in the operator's telephone set and is then started toward normal position, it will be thrown toward normal position by the actuating springs and its inertia will carry it a considerable distance beyond the normal plane and the rollers will land against the dummy springs, but, as before stated, these dummy springs are given sufficient leeway of motion so that the blow struck them by the returning cam lever will not move them a sufficient distance to affect in any way the other contact springs of the ringing sets, and it is only after the key is manually moved a much greater distance into the ringing position that the dummy springs will be moved sufficiently to carry the contact springs 11 from the normal springs 12 and into engagement with the alternate springs 13. In practice the normal springs 12 are connected with the cord strand sections of the calling side and the contact springs 11 normally connect with the cord strands of the called side, and if the actuating contact springs were moved sufficiently upon recoil of the key to break contact between springs 11 and 12, the cord circuit would be opened for an instant, which would produce a disagreeable click in the

subscriber's telephone, hence the importance of means such as the dummy springs for preventing such circuit disturbances.

The key shown and described is only one of the many forms for carrying out my invention, the broad and main feature of which lies in the provision of springs means which will assist in balancing the key in a normal position without in any way affecting the efficient operation of the associate springs, and which will take up the recoil of the cam lever without in any way affecting the position or operation of the associate springs.

Having thus described my invention, I desire to secure by Letters Patent the following claims:

1. In a telephone key, the combination of a supporting frame, an actuating lever, a stationary contact spring, a movable contact spring, and a flexible member for transmitting the movement of the key to the movable contact spring, said member having independent movement before engaging said contact spring said independent movement effecting no change in the circuits controlled by the key.

2. In an operator's telephone key, the combination of a supporting frame, a stationary spring supported from the frame, a movable spring supported from the frame, an actuating spring member disposed between the contact springs, an actuating lever engaged by said actuating spring, said actuating spring being normally disconnected from the contact springs and adapted upon actuation of the lever to be first moved alone and then with the movable contact spring to change the contact relations between the contact springs.

3. In an operator's telephone key, the combination of a supporting frame, two contact springs supported from said frame, an actuating spring member extending between the contact springs but normally disconnected from their contact ends, a key lever associated with the actuating spring, actuation of said key lever causing said actuating spring to move first alone and then to change the contact relations between the contact springs.

4. In an operator's telephone key, the combination of a supporting frame, a plurality of contact springs extending from the supporting frame, an independent actuating member associated with the contact springs, a key lever associated with the actuating member, actuation of the key lever causing the actuating member to move first alone and then to actuate the contact springs to change their contact relations.

5. In an operator's telephone key, the combination of a supporting frame, parallel contact springs extending from the supporting frame and having contact points at their

ends, a key lever, an independent actuating member extending parallel with the contact springs and beyond said springs into engagement with the key lever, said actuating member being normally separated from the ends of the contact springs whereby actuation of the key lever will cause independent movement of the actuating member through a considerable distance before said actuating member causes actuation of the contact springs.

6. In an operator's telephone key, the combination of a supporting frame, a middle contact spring, an inside contact spring, an outside contact spring, said springs being parallel with each other and supported from the frame, a key lever pivoted from the frame above the contact springs, a dummy spring extending upwardly between the springs and into engagement with the key, said dummy spring being normally disconnected from the contact springs whereby when the key is actuated said dummy spring may first move independent of the contact springs before engaging therewith to change their contact relations.

7. In an operator's telephone key, the combination of contact springs adapted for connection with telephone circuits, a key lever and a dummy spring member associated with the contact springs and adapted to be engaged by the key lever when actuated, said dummy spring being normally disconnected from the contact springs so that upon actuation of the key lever said dummy spring will first move independently and then engage with the contact springs to alter the contact relations.

8. In an operator's telephone key, the combination of contact springs adapted for connection with circuits, a key lever, a dummy spring associated with the contact springs and engaging with the key lever, said dummy spring assisting in holding the key lever in its normal position and said dummy spring being normally disconnected from the contact springs, actuation of the key lever causing the dummy spring to move first alone and then to change the contact relations of the contact springs.

9. In an operator's ringing and listening key for telephone systems, the combination of a key lever, a set of ringing circuit-controlling contact springs, a set of operator's telephone circuit-controlling contact springs, actuating means extending from the operator's telephone circuit-controlling springs to be engaged by the key lever, actuating means extending from the ringing circuit-controlling springs to be actuated by the key lever, said actuating means normally retaining the key lever in a normal position, means for locking the key lever after it has been moved to engage the actuating means of the operator's telephone circuit-controlling springs,

and means for preventing disturbance of the contact relations of the ringing circuit-controlling contact springs when the key lever is thrown back to its normal position.

5 10. In a telephone key, the combination of a supporting frame, an actuating lever, a movable contact spring, and a flexible member for transmitting the movement of the key to the movable contact spring, said member having independent movement before en-

gaging said contact spring, said independent movement effecting no change in the circuits controlled by the key.

In witness whereof, I hereunto subscribe my name this 25th day of July A. D., 1907. 15

RAY H. MANSON.
